United States Patent Office.

GEORGE W. HERRING, OF BANGOR, MAINE.

Letters Patent No. 97,398, dated November 30, 1869; antedated November 27, 1869.

IMPROVEMENT IN AUGER-HANDLES.

The Schedule referred to in these Letters Patent and making part of the same.

To all whom it may concern:

Be it known that I, GEORGE W. HERRING, of Bangor, in the county of Penobscot, and in the State of Maine, have invented new and useful Improvements in Auger-Handles; and do hereby declare that the following is a full, clear, and exact description thereof, reference being had to the accompanying drawings, and to the letters of reference marked thereon.

The nature of my invention consists in the construction and general arrangement of an "auger-handle," by which the shank of the auger is held firmly in its place, and can readily be removed and inserted, at pleasure.

In order to enable others skilled in the art to which my invention appertains, to make and use the same, I will now proceed to describe its construction and operation, referring to the annexed drawings, which form a part of this specification, and which represent a longitudinal vertical section of my improved auger-handle.

A represents the wooden handle, which has a hole through its centre, for the insertion of the shank B of the auger.

Around the centre of the handle A is placed a metal collar, C, having a hole corresponding with the hole through the wooden handle.

One half of this collar is not as thick as the other half, the line of division being through the centre of the hole above mentioned.

The thinner end of the collar is provided with screw-

threads, on which is placed a nut, D; and between said nut and the larger portion of the collar C is placed a ring or washer, E, of such thickness as to make the outer surface smooth and even.

The washer E is provided with notches, in size a little less than one-half of the hole in the collar C.

When it is desired to insert the auger-shank B in the handle, the nut D is loosened, when the washer E is moved slightly outward. The shank is then inserted, and the nut tightened, when the notches in the washer, closing against the shank, hold it firmly.

In the outer edge of the washer E are two slots or notches, a a, through which are inserted pins e e into the collar, so that the washer can only be withdrawn a certain distance, and, consequently, cannot come off, and be lost.

Having thus fully described my invention,

What I claim as new, and desire to secure by Letters Patent, is—

The arrangement, on the handle A, of the collar C, slotted washer or ring E, pins b b, and nut D, all constructed and operating substantially as and for the purposes herein set forth.

In testimony that I claim the foregoing, I have hereunto set my hand, this 24th day of March, 1869.

GEORGE W. HERRING.
